Primary Examiner — Shannon W Morgan*Assistant Examiner* — Arva P Adams(74) *Attorney, Agent, or Firm* — Skaar Ulbrich Macari, P.A.(57) **CLAIM**

We claim the ornamental design for a bottle, as shown and described.

DESCRIPTION

FIG. 1 is a perspective view of a bottle showing the claimed design.

FIG. 2 is a first side view of the bottle of FIG. 1.

FIG. 3 is a second side view of the bottle of FIG. 1.

FIG. 4 is a top view of the bottle of FIG. 1; and,

FIG. 5 is a bottom view of the bottle of FIG. 1.

The broken lines shown are for the purpose of illustrating portions of the bottle and form no part of the claimed design.

1 Claim, 5 Drawing Sheets(56)
